US0D1110297S

(12) **United States Design Patent** (10) **Patent No.:** **US D1,110,297 S**
(45) **Date of Patent:** **** Jan. 27, 2026**

(54) **TELEVISION RECEIVER**

(71) Applicant: **LG DISPLAY CO., LTD.**, Seoul (KR)

(72) Inventors: **Sunghyun Heo**, Paju-si (KR); **Jaehan Kim**, Paju-si (KR); **Sangyoon Byun**, Paju-si (KR); **Lisie Park**, Paju-si (KR); **Hongseok Seo**, Paju-si (KR); **Minkwan Seo**, Paju-si (KR)

(73) Assignee: **LG DISPLAY CO., LTD.**, Seoul (KR)

(**) Term: **15 Years**

(21) Appl. No.: **29/942,177**

(22) Filed: **May 14, 2024**

Related U.S. Application Data

(63) Continuation of application No. 35/516,519, filed on May 6, 2022 (U.S. filing date under 35 U.S.C. 384), and having an international filing date of May 6, 2022, now Pat. No. Des. 1,032,551.

CLAIM

The ornamental design for a television receiver as shown and described.

DESCRIPTION

FIG. 1 is a front, right, top perspective view of a television receiver showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear, left, bottom perspective view thereof.

The broken lines depict portions of the television receiver that form no part of the claimed design.

1 Claim, 8 Drawing Sheets
